UNITED STATES PATENT OFFICE.

FREDERIC A. LANE, OF NEW HAVEN, CONNECTICUT, ASSIGNOR OF ONE-HALF TO FRANK E. MORGAN, OF SAME PLACE.

OIL CAN.

SPECIFICATION forming part of Letters Patent No. 495,223, dated April 11, 1893.

Application filed July 11, 1892. Serial No. 439,579. (No model.)

To all whom it may concern:

Be it known that I, FREDERIC A. LANE, of New Haven, in the county of New Haven and State of Connecticut, have invented a new 5 Improvement in Oil-Cans; and I do hereby declare the following, when taken in connection with accompanying drawings, and the letters of reference marked thereon, to be a full, clear, and exact description of the same, and 10 which said drawings constitute part of this specification, and represent, in—

Figure 1, a side view of the can complete; Fig. 2, a vertical section of the same; Fig. 3, a vertical central section with the cap removed; Fig. 4, the spindle detached.

This invention relates to an improvement in that class of oilers which are provided with some means for closing the ejector-tube, so as to prevent the escape of oil, such oilers being 20 specially adapted for the pockets of cycles, and other purposes where it is necessary to prevent the accidental escape of oil through the ejector-tube, the object of the invention being to provide the oil-can with means for 25 conducting the oil from the ejector-tube to the desired point, and in a regulated or limited quantity, and the invention consists in the construction as hereinafter described and particularly recited in the claims.

30 The body A, of the oil-can is preferably made of cylindrical shape, and this is best made from a sheet-metal tube, closed at the bottom. The bottom B, is made from elastic sheet-metal, and of concavo-convex shape 35 with the convex surface outside, and so that that convex surface may be depressed to operate as a compressor on the contents of the can, as a means to force ejection. At the upper end of the can a neck C, is attached or 40 made as a permanent part of the can; this neck is constructed with an annular flange D, upon which rests a hard rubber packing E. The neck is tubular, and into the neck the ejector-tube F, is screwed, as shown, so that

45 it may be removed for the purpose of filling the can. The neck projects above the packing-collar E, and is screw-threaded upon its outside.

50 G, represents a cap, the cavity in which is somewhat deeper than the depth of the pro-

jecting ejector-tube, and at its open end is screw-threaded corresponding to the screw-thread on the neck, and so that it may be screwed thereon down upon the packing E, as seen in Fig. 2. Within the cap and at the 55 end of the cavity therein, a flexible plug H, is introduced, to fill that end of the cap, and so as to become stationary therein. This plug is adapted to bear against the end of the ejector-tube, and so that when the cap is 60 screwed down, this plug comes to a close bearing upon the end of the ejector-tube, and so as to securely close that end against the possibility of the escape of oil. Any oil which shall work through the screw-thread around 65 the ejector-tube, as it naturally and unavoidably will do, will pass into the cap, but it cannot escape therefrom because of the packing E, upon which the cap closely fits, so that while possibly the oil may escape around 70 the ejector-tube, as in all constructions of oil-cans it will do, the oil so escaping cannot escape from the cap, but will be retained within the cap. The amount of oil so escaping around the ejector-tube is slight, but no 75 matter how slight that escape is, it is desirable to prevent the possibility of contact between the oil so escaping, and surrounding objects, or to prevent its flow onto the outside of the can as it will do in cans where there is 80 no protection of this cap-like character.

By the peculiar construction of the cap and packing, the oil is prevented from escaping onto the exterior of the can, so that the soiling of the fingers or articles with which the 85 can may come in contact is avoided.

Within the can a spiral spring I, is arranged, one end bearing upon the elastic bottom B, of the can, and the other end toward the tube end of the can.

90 J, represents a spindle which is arranged through the ejector-tube, and is of a length considerably greater than the length of the tube; it is best made from wire and tapering. A bend K, is formed in the wire at a point 95 distant from the end greater than the length of the ejector-tube, and so as to form a shoulder or stop within the can. The spindle is constructed with a tail L, which extends down into the spring, and the spring bears against 100

the shoulder K, on the spindle. When the cap is in place on the can, as seen in Fig. 2, the spindle is forced down through the tube, and compresses the spring, but when the cap is removed, as seen in Fig. 3, the spring forces the spindle outward, and so as to project the end of the spindle to a considerable distance beyond the end of the tube. The diameter of the spindle is less than the internal diameter of the tube, so that there will be a practical oil-space within the tube around the spindle when it is so projected, as seen in Fig. 3. The shoulder K, strikes the inner end of the ejector-tube, and so as to arrest the spindle when the desired extent of projection is produced. The spindle thus projected serves as a conductor for the oil, and so as to lead it to any desired point, the oil following the spindle after it leaves the tube, and so that the quantity of oil flowing may be readily seen. To eject the oil, the spring-bottom B, is employed, the thumb is placed upon that bottom, and pressure is produced accordingly as more or less oil is required. Without the spindle the pressure upon the bottom would eject a quantity of oil corresponding to the passage through the tube, that passage is necessarily of some considerable extent in order to prevent its clogging, the result of the use of such a tube without the spindle is that a much greater quantity of oil is generally ejected than is required or desirable, but by the introduction of the spindle the passage through the tube is very considerably contracted, and the movement of the spindle through the tube as in the opening and closing of the cap keeps that passage clear. Again, the spindle is free in the tube when the cap is removed, and if the end of the spindle be applied to the point where the oil is to be conducted, a slight pressure on the can will cause the spindle to move inward, and so that an up and down movement of the can toward and from the point to be oiled, will cause a play on the spindle, and a consequent free but limited flow of oil.

The spindle does not operate in any sense as a valve, and care must be taken that the shoulder which is formed to limit the movement of the spindle shall be such as by no

possibility to close, or to any considerable extent, interrupt the passage of oil into the tube.

The shoulder is formed in the manner described as being a convenient way of producing that shoulder, and so as to prevent possible clogging of the passage, the extent of the shoulder is less than the diameter of the opening through the neck into which the tube is placed, so that the spindle may be readily removed or introduced as occasion may require.

I claim—

1. An oil-can of substantially cylindrical shape, and provided with a concavo-convex elastic bottom, an ejector-tube at the upper end of the can, combined with a spiral spring 65 within the can, a spindle through the ejector-tube, of less diameter than the internal diameter of the tube, and constructed with a shoulder within the can, the length of the spindle from the shoulder to its point being greater 70 than the length of the ejector-tube, the said spiral spring adapted to bear upon the spindle with a tendency to force the spindle outward when free so to do, and a cap over the ejector-tube, and adapted to force the spindle into the can and close the end of the tube, 75 substantially as described.

2. An oil-can, the body of which is of substantially cylindrical shape, constructed with a concavo-convex elastic bottom, the upper 80 end of the can provided with a neck, and an ejector-tube therein, combined with a spindle through said ejector-tube, of a length greater than the length of the said tube, but of less diameter than the internal diameter of the 85 tube, the spindle constructed with a shoulder within the can adapted to limit the extent of projection of the spindle, and a spiral spring within the can adapted to bear upon the said spindle with a tendency to yieldingly force it 90 outward through the tube, substantially as described.

In testimony whereof I have signed this specification in the presence of two subscribing witnesses.

FREDERIC A. LANE.
